UNITED STATES PATENT OFFICE.

NEVILLE HUNSBURGER, OF ALDEN, PENNSYLVANIA, ASSIGNOR TO SAMUEL STERN-BERGER, OF PHILADELPHIA, PENNSYLVANIA.

SAFETY-PIN.

1,192,522.

Specification of Letters Patent. Patented July 25, 1916.

Application filed May 1, 1915. Serial No. 25,169.

To all whom it may concern:

Be it known that I, NEVILLE HUNSBURGER, a citizen of the United States, residing at Alden, in the county of Delaware and State of Pennsylvania, have invented a new and useful Safety-Pin, of which the following is a specification.

Heretofore the guard or shield of a safety pin which is adapted to receive and interlock the point portion of the pin proper thereof has been formed with inturned lips on which are well defined shoulders on which a reduced neck on said portion is adapted to be seated, but said neck is held with severity on said shoulders whereby much more than usual force is required to displace it from said shoulders, in order to remove the pin proper from said guard or shield, so as to open the device preparatory to disconnecting it from the article to which it is applied.

My invention is designed to overcome said objection and it consists in providing the guard with inturned humps and in adapting the neck of the pin proper to be gripped or clamped by the same so as to be firmly held in the guard or shield, while the under portion of said neck will be below said humps so as to be uncontrolled by the latter, whereby the holding power of the humps on the neck may be overcome by an ordinary amount of power applied to the pin proper, when the neck will readily spread apart the humps and pass the same, causing greater ease in the disconnecting movement of the pin proper from the shield or guard.

The invention is satisfactorily illustrated in the accompanying drawing, but the important instrumentalities thereof may be varied, as long as they are included in the scope of the claims.

Figure 1 represents a side elevation partly broken away of a safety pin embodying my invention. Fig. 2 represents an elevation on an enlarged scale taken from the inner end of the guard or shield, and the portion adjacent thereto. Fig. 3 represents a similar elevation including sections of the point portion of the pin proper and back member thereof. Fig. 4 represents a longitudinal section on an enlarged scale of a portion of the guard or shield, and elevation of a portion of a lip thereon together with the point portion of the pin proper in dotted lines. Fig. 5 represents a side elevation of said

point portion. Fig. 6 represents what may be termed a plan view of said point portion. Fig. 7 represents a section of the guard or shield on the line $x-x$ Fig. 2. Fig. 8 represents a perspective view of a detached portion thereof. Fig. 9 represents a partial transverse section and partial end view of a modification. Fig. 10 represents an elevation of a portion of the pin proper with the neck thereof of modified form.

Similar numerals of reference indicate corresponding parts in the figures.

Referring to the drawings:—1 designates the pin proper of a safety pin, 2 the point portion thereof, 3 the back member, 4 the coil or spring of the device, and 5 the guard or shield which is bent on itself to form side walls and a back, it being adapted to receive said point portion, which features broadly considered are well known.

In the sides of the point portion 2 are grooves which form the reduced neck 7 on said portion, the side faces 8 of said neck in the vertical position of the device in which it is placed in the drawings being somewhat of greater depth than the thickness of the adjacent portion of the pin.

On the inner end of the side walls of the guard or shield are the inturned resilient lips 9, the portions of their edges intermediate of their ends removed from the back 10 of the guard or shield 5 being projected inwardly forming the humps 11 which face each other leaving between them the passage 12 which primarily is narrower than the thickness of the neck 7. The edges of said humps or swells are curved from top to bottom so as to present crowns at or about the medium horizontal line of the humps.

The operation is as follows. The point portion of the pin 1 is introduced into the guard or shield from below, when said neck 7 enters the passage 12 and bears laterally against the humps 11 forcing them apart in lateral directions. Then the crowns of the humps owing to the resiliency of the lips press inwardly against the side faces of the neck and so hug and press-up the neck, thus controlling the latter, and consequently the point portion of the pin in the guard or shield preventing improper or accidental displacement of the pin proper and opening of the device. A portion of the neck is below said crowns and so the neck is not obstructed by said crowns or the swells them-

selves whereby when it is desired to open the device by removing the point-portion of the pin proper from the shield, said pin proper is pushed or drawn downwardly, so that the holding power of the humps on the neck is overcome, and the latter rides freely down said humps, and so reaches the lower terminal of the shield, when it is moved laterally therefrom and so disconnected and removed from the shield as usual.

The neck 7 is made tapering in cross section, the narrow end being below, as most plainly shown in Fig. 3, whereby when the point portion of the pin rises in the shield, the wide portion of the neck contacts with the crowns of the humps and spreads apart the lips 9, fully separating the humps allowing the point portion to rise in the shield to full extent when the humps press against the tapering sides of the neck above the bottom of the latter with an action somewhat upwardly so that the neck, and consequently the pin point will remain in its controlled position in the guard, it being evident that this upward action or pressure of the humps on the tapering or slant sides of the neck is constant, this being due to the crowns of the humps pressing inwardly and so upwardly against the slant or tapering sides of the neck 7, thus serving to raise the pin 1 and hold its neck 7 against the back of the guard 5 without liability of the pin returning therefrom or opening, unless when subjected to superior force, in which latter case the neck rides downwardly over the crowns of the humps without being severely resisted by said crowns, thus separating the humps, when said neck will move freely through the passage 12 and so clear the humps when the pin may be turned laterally from the guard for opening purposes.

It is evident that one of the humps may

Copies of this patent may be obtained for five cents each, by addressing the "Commissioner of Patents, Washington, D. C."

be dispensed with, in which case, the pin has its neck made with a recess on one side only, both features being in Figs. 9 and 10, 45 so that the face 8 of said recessed side is engaged by the single existing hump 11, while the portion of the pin opposite to the recess rests against the adjacent side wall 13 of the guard, the neck, however, being engaged by the hump 11, and subject to the frictional contact therewith and the lateral and upward pressure thereon.

Having thus described my invention what I claim as new and desire to secure by Letters Patent, is:—

1. In a safety pin, a pin proper having on its point portion a neck, the side faces of which are tapering, and a shield composed of a back and side walls and having on the inner terminals of said walls inwardly-extending lips, the inner edges of which have swells thereon, said side faces of the neck being adapted to be engaged by said swells and pressed thereby upwardly toward said back of the shield and held resiliently thereat.

2. In a safety pin, a pin proper having on its point portion a neck, the side faces of which are tapering, and a shield composed of a back and side walls and having on the inner terminals of said walls inwardly-extending lips, the inner edges of which have swells thereon, said side faces of the neck being adapted to be engaged by said swells and pressed thereby upwardly toward said back of the shield and held resiliently thereat, the lower portion of said neck being comparatively free of said swells.

NEVILLE HUNSMERGER.
